UNITED STATES PATENT OFFICE.

WILLIAM W. DINGEE, OF RACINE, WISCONSIN, ASSIGNOR TO THE J. I. CASE
THRESHING MACHINE COMPANY, OF SAME PLACE.

DESIGN FOR A CASING FOR THRASHING-MACHINES.

SPECIFICATION forming part of Design No. 18,793, dated December 11, 1888.

Application filed October 25, 1888. Serial No. 289,165. Term of patent 14 years.

To all whom it may concern:

Be it known that I, WILLIAM W. DINGEE, a citizen of the United States, residing at Racine, in the county of Racine and State of Wisconsin, have invented and produced a new and original Design for the Frame or Body of the Separator of Thrashing-Machines; and I do declare the following to be a full, clear, and exact description of the same, reference being had to the accompanying drawings, forming a part thereof.

My invention relates to a design for the casing of a thrashing-machine; and it consists in a new and original shape for the said casing, as fully disclosed in the following specification and claim.

In the drawings forming a part of this specification, Figure 1 is an isometrical perspective view of a thrashing-machine embodying my design. Fig. 2 is a top view of the same.

In the drawings, A designates the main body of the casing, which is of rectangular form in plan view, as shown in Fig. 2. Forward of this portion of the casing is the for-

wardly-extending portion A', which is narrower than the main body A of the casing and forms a part of the same, and this narrower portion is connected to the portion A by walls which incline outwardly from the narrower portion of the casing to the wider portion, as shown in the drawings. The narrow and inclined portions of the casing have a base or bed of the same width as the main body of the casing; but this bed may conform to the shape of the casing A' without departing from my design.

What I claim, and desire to secure by Letters Patent, is—

The design for the casing of a thrashing-machine herein shown and described, the same consisting of the main body of rectangular form in plan view and a forwardly-extending narrower portion.

In testimony whereof I affix my signature in presence of two witnesses.

WILLIAM W. DINGEE.
